UNITED STATES PATENT OFFICE.

BENJAMIN J. MULLEN, OF COLUMBIANA, OHIO.

TAPPING MACHINE FOR METALLURGICAL FURNACES.

Application filed February 26, 1926. Serial No. 90,956.

In my United States Patents Nos. 1,276,251 and 1,276,252 there are disclosed machines for tapping the iron notches of blast furnaces, and in the first of these patents there is explained in detail some of the difficulties encountered in such operations. These machines have been successfully used in a number of plants, and where used they have entirely displaced the manual tapping of blast furnaces, and have made it possible to tap them rapidly and without injury or liability of injury to workmen.

The present invention relates to machines of the same general character as those disclosed in my said patents, although the machine provided according to this invention is applicable also to the tapping of open hearth and other metallurgical furnaces as well as of blast furnaces.

The object of the present invention is, generally stated, to improve the construction and consequent operation of the machines shown in my earlier patents.

A specific object is to provide a machine the operation of which, after having been placed in notch-opening position, may be completely controlled at a safe distance from a furnace to perform an entire tapping operation, and which, after the tapping is completed, may be removed from its tapping position without the necessity of a workman going near the machine or furnace.

A further specific object is to provide a machine in which the resistance to the tapping strokes of the machine is removed from its feed mechanism thereby eliminating wear upon such mechanism.

A further specific object is to improve the mechanism for supporting such machines and anchoring them during tapping operations, and to provide mechanical means for releasing the anchoring mechanism at the completion of a tapping operation.

Still further specific objects are to eliminate wear between the moving parts of the tapping engine and their supports, and to improve the mechanism for axially rotating a tapping drill or other tool.

The invention is illustrated in the accompanying drawings of which Fig. 1 is a side elevation of the machine in operative position beside a blast furnace, a portion of the furnace being shown in section; Fig. 2 a side view of the machine to enlarge scale, a pro-

tection hood for the machine being partially removed and a portion of the frame of the machine being shown in section to more clearly illustrate the construction of certain parts of the machine; Fig. 3 a plan view of the machine as seen in Fig. 1 with the protection hood entirely removed; Fig. 4 a plan view to enlarge scale of mechanism for automatically rotating a tapping tool during a tapping operation; Fig. 5 a side view of the mechanism shown in Fig. 4; Fig. 6 an elevation to enlarge scale of mechanism for resisting the thrust of a tapping tool by the frame of the machine; Fig. 7 a transverse sectional view taken on the line VII—VII, Fig. 6; Fig. 8 a horizontal sectional view taken on the line VIII—VIII, Fig. 7; Fig. 9 a plan view of the mechanism shown in Figs. 6 and 7; Fig. 10 a diagrammatic view showing the control mechanism of the machine; and Fig. 11 a plan view to enlarge scale of the top of an electric controller used in the operation of the machine.

The main elements of my improved machine are the same as those of the machines shown in my prior patents. In other words, the present machine comprises an elongate frame having side members 1 and 2 and end members 3 and 4, a reciprocating fluid pressure engine supported on these side members and comprising a cylinder 5, piston rod 6 and cross head 7. To eliminate wear incident to the movement of cylinder 5 and cross head 7 upon the frame side members, these parts of the engine are preferably provided with rollers 8 which ride upon the tops of inturned flanges of the frame side members. By so supporting the cylinder and cross head, any grit which may be deposited upon the flanges of the frame side members will not result in undue wear upon such members and upon the parts of the cylinder and cross head which they support.

Cylinder 5 of the reciprocating engine is fed forwardly preferably by means of a reversing electric motor 10, the armature shaft of which may be provided with a pinion 11 meshing with a gear 12 attached to a rotatably mounted feed screw 13 extending longitudinally of the frame below the engine. This feed screw is engaged by a pair of internally threaded arms 14 extending downwardly from the lower side of cylinder 5, the arrangement being such that the

operation of motor 10 in one direction or the other will, through the train of driving connections just explained, cause cylinder 5 to move forwardly or rearwardly upon the frame side members of the machine. For operating the engine to effect a reciprocation of its piston rod 6, pressure fluid such as compressed air or steam is led to the machine through a flexible pipe 16 (Fig. 2) connected at the rear end of the machine to a pipe 17 which extends to the forward end of the machine and is supported by transverse frame yokes 18 and 19. At its forward end pipe 17 is connected to a pipe 20 telescopically connected to a pipe 21 leading to the valve chest of the engine cylinder, these pipe connections being such that as engine cylinder 5 is moved longitudinally upon the frame motive fluid may be supplied to it at all of its positions. While the screw 13 is normally rotated by motor 10 to move the engine, it may also be rotated by a hand crank 22 attached to a rotatable shaft 23 (Fig. 3) having bevel 25 pinion connections 24 with the forward end of the screw.

In the machine of each of my prior patents provision is made for attaching a drill rod to the cross head of the tapping engine for drilling a notch nearly to the point of molten metal, and provision is further made for then substituting a tapping rod for the drill rod and using the cross head of the engine for hammering the tapping rod. This substitution was made primarily to prevent the burning of drill rods formed of expensive tool steel. In the use of those machines it has been found that the notches may be entirely opened by drill rods formed of metal which is no more expensive than that customarily used in the manufacture of tapping rods, and that therefore the burning of a drill is of no material consequence. Accordingly, the present machine is constructed for opening notches entirely by drill rods, although it will be understood that the invention is not limited to machines which operate in this particular manner.

Referring again to the drawings, particularly Figs. 4 and 5, a drill rod 25 is shown as being attached to a drill spindle 26 by a chuck 27 attached to the end of the spindle which is rotatably mounted in cross head 7. While any suitable form of chuck 53 may be used, it may conveniently consist of a collar provided with a set screw 28.

Provision is made for automatically rotating drill spindle 26 upon each reciprocation of piston rod 6 so that the drill rod attached to the spindle may be properly turned during a tapping operation. For this purpose spindle 26 has attached to it a bevel pinion 30 which meshes with a bevel pinion 31 attached to a stub shaft 32 which is rotatably mounted in a bracket 33 projecting

from the forward end of cross head 7. The outer end of shaft 32 has keyed to it a ratchet wheel 34, and between such wheel and the side of bracket 33 there is rotatably mounted on shaft 32 an arm 35 provided with a pawl 36 adapted to engage the teeth of the ratchet wheel. The outer end of arm 35 is connected by a link 37 to cylinder 5 so that upon each rearward movement of the cross head ratchet wheel 34 is rotated to 70 in turn rotate the drill through the connections just explained. By this simple arrangement the drill rod may be rotated as much as 70° upon each reciprocation of the cross head, and such rotation effectively prevents cornering of the drill during a tapping operation.

A further feature of my invention has to do with the provision of means for preventing undue wear upon feed screw 13 by reason of drilling impact. To this end there is attached to cylinder 5 automatically operated and controlled mechanism for firmly engaging the frame of the machine during the intervals between the forward feeding of cylinder 5 to advance a drill rod in a notch being opened. While such mechanism may be operated and controlled either electrically or pneumatically (it being understood that the machine requires electric current for operating motor 10 and pressure fluid for operating the reciprocating engine), it is preferably operated by pressure fluid mechanism. This mechanism preferably acts through a system of floating 90 equalizing levers to operate clamps which engage the inturned flange of frame side members 1 and 2.

Referring now particularly to Figs. 6-9, the forward end of engine cylinder 5 has attached to it a bracket 45 on top of which there is mounted a small pressure fluid cylinder 46 provided with a piston 47 connected to a rod 48 extending downwardly through the head of the cylinder. As will presently appear, it requires but a slight movement of piston 47 to operate the frame-gripping clamps. This movement is effected by pressure fluid led to cylinder 46 through a pipe 49.

Projecting forwardly from each side of bracket 45 there are bolts 50 and 51 (Fig. 6) arranged one above and one below the inturned flange of a frame side member. Around each bolt 50 there is a bearing block 52, the interior diameter of which is slightly larger than the diameter of the bolt. This block extends between the outer face of bracket 45 and a nut 53 on bolt 50, such nut being screwed upon the bolt to a position where there is sufficient clearance between the nut and the adjacent end of block 52 to permit the block to freely move vertically upon bolt 50. Nut 53 may be firmly held in this position by a lock nut 54. In 130

a manner similar to this bolt 51 is provided with a bearing block 55.

Extending between piston rod 48 and bearing blocks 52 and 55 on each side of the machine there is a system of floating and equalizing levers for engaging these blocks and pressing them firmly upon the flanges of the frame. As shown in the illustrative embodiment of the invention this system of levers comprises a bar 60 pivoted at its center to the lower end of rod 48 and pivotally connected at its outer end to the upper ends of a pair of links 61, the lower ends of which engage pins 62 (Fig. 8). To each pin 62 is attached a pair of bars 63 provided at their ends with laterally extending bearing pins 64 pivotally engaged by the upper ends of links 65. Each pair of bars 63 is also provided intermediate of its ends with a pin 66 on which there is pivotally mounted an arm 67 of a lever which includes also two other arms 68 and 69. Arm 68 of this lever is provided with a set screw 70 adapted to bear upon the top of bearing block 52, and arm 69 is pivotally connected at its lower end to an arm 71 of a lever which also includes two other arms 72 and 73. Arm 72 of this lever is provided with a set screw 74 adapted to bear upon the lower face of bearing block 55, and arm 73 is pivotally connected to the lower end of links 65.

In a manner presently to be explained, motive fluid is supplied to cylinder 46 to cause its contained piston 47 to move to and remain in its uppermost position at all times during the operation of the machine except when motor 10 is operating to move engine cylinder 5 longitudinally on the frame. The weight of the system of clamp-operating levers normally causes the lower ends of set screws 70 to bear upon blocks 52, but such bearing is not sufficient to prevent free sliding movement of these blocks upon the upper faces of the inturned flanges of the frame side members. Upward movement of piston 47 acts through bar 60, links 61 and bars 63 to move links 65 downwardly, which causes their arms 72 to move upwardly so that their set screws 74 bear upon the lower faces of bearing blocks 55. It will thus be seen that the upward movement of piston 47 causes both pairs of bearing blocks 52, 55 to grip the upper and lower faces of the frame flanges and thereby hold the cylinder against longitudinal movement upon the frame. This clamping of the cylinder to the frame removes from the feed screw resistance to the impact of the drill rod and therefore greatly reduces wear upon the screw.

It will be understood from the foregoing explanation of the clamping mechanism that when piston 47 is elevated by the pressure of fluid acting upon piston 47 the clamps

engage the frame of the machine, and that when pressure fluid is exhausted from cylinder 46 containing piston 47 the weight of the piston and rod and levers attached to it causes the piston to move downwardly to release the clamps. It will also be understood that the cylinder is clamped to the frame while the engine is stationary with relation to, or in other words, is not moving upon, the frame, and that the clamps are released while the cylinder is moved longitudinally to advance or withdraw the drill rod. That this operation may be automatically effected, control of motive fluid through pipe 49 leading to cylinder 46 is co-ordinated with the controller for operating motor 10.

As seen in Fig. 10, at the rear of the machine pipe 49 is connected by a T fitting to a pipe 80 provided with two valves 81 and 82. Valve 81 is connected to a pipe 83 leading from a source of pressure fluid supply, and controls flow of pressure fluid through a pipe 75 leading to cylinder 46, through pipes 76, 77, 78 and 49, pipe 78 being telescopically connected to pipe 77 for the purpose explained with reference to pipes 20 and 21. The outlet of valve 81 is open to atmosphere to permit exhaust fluid from cylinder 46 to escape through the pipe connections just explained. These two valves are provided with operating stems 84 and 85 adapted to be moved upwardly by electromagnets or solenoids 86 and 87, respectively, the valves being closed by the downward movement of stems 84 and 85 due to their weight when the solenoids are deenergized.

In Fig. 10 there is diagrammatically represented a controller 90 for controlling flow of current to motor 10, and in Fig. 11 there is shown a plan view of the top of the controller and of its operating handle 91, the top of the controller having contactors indicated on it for controlling the supply of current to the motor and making and breaking circuits through magnets 86 and 87. In the central position of controller handle 91 shown in Fig. 11 the motor is idle and central contactor 92 closes a circuit through magnet 86 to energize it to open valve 81. Pressure fluid then flows from pipe 83 through valve 81, pipe 80, and pipe 75 and its connected pipes to cylinder 46 to cause the clamps to engage the frame. When the indicating point of handle 91 is turned to the left and is opposite contactor 93 the circuit through magnet 86 is broken to permit valve 81 to become closed, and a circuit is closed through magnet 87 to open valve 82 to permit exhaust pressure fluid to escape from cylinder 46. This permits the clamps to become disengaged from the frame. Further movement of the indicating point of handle 91 to a position opposite contactor

94 causes current to be supplied to motor 10 to move cylinder 5 forwardly. The same operation takes place when the motor is reversed to move cylinder 5 backwardly, magnet 87 being first energized when the pointer of controller 90 is opposite contactor 95, and current being supplied to the motor when the indicating point of the controller handle is opposite contactor 96.

10 From this explanation of the construction and operation of valves 81 and 82 and of the controller for making and breaking circuits through their operating solenoids and for supplying current to the motor, it will 15 be understood that the motor can not be operated to move engine cylinder 5 either forwardly or rearwardly without first releasing the clamps, and also that when the motor is idle the clamps engage the frame 20 and thereby lock the engine cylinder to it.

A further feature of the present invention has to do with means for locking the machine in position for tapping a notch. Before a notch is tapped it is seldom dangerous 25 for workmen to be near it, but when the tapping has proceeded to a point where molten metal is nearly reached, as well as after it has been reached, it is dangerous for a workman to be near the notch. To avoid 30 the necessity of a workman at or near a machine to disengage it from its anchorage, provision is made for doing this mechanically by apparatus controlled at a safe distance from the machine.

35 Having reference particularly to Figs. 1, 2 and 3, a trough 100 leading from a notch 101 in the bottom of a blast furnace 102 is provided at its sides with upwardly extending lugs 103, each adapted to be engaged between a bracket 104 and the lower end of a lever 105 pivoted intermediate of its ends to a lug 106 forming a part of the bracket. These brackets are clamped to the lower 40 portions of the frame side members by bolts 45 107, which engage suitable slots 108 in the frame so that the clamps may be suitably adjusted to the proper position for holding the machine in position for tapping. The upper end of each lever 105 is connected by 50 a link 109 to a piston rod 110 attached to a piston 111 in a fluid pressure cylinder 112 fastened to the side of the machine. Piston 111 may be urged rearwardly by a spring 113 and forwardly by means of pressure 55 fluid supplied to cylinder 112 through a pipe 114 connected to fluid pressure supply pipe 83. When the machine is arranged in tapping position with lugs 103 engaged between the clamp brackets 104 and lever 105, pressure fluid is supplied through pipes 60 114 to cause levers 105 to engage the lugs, and as long as pressure fluid is so supplied the machine is clamped firmly in tapping position. At the end of a tapping operation 65 the supply of pressure fluid is shut off and

its supply pipe thrown to exhaust so that springs 113 in cylinders 112 cause piston 111 to move rearwardly to release levers 105.

As has been previously indicated, provision is made for controlling the operation 70 of the machine at a safe distance from it so that a notch may be completely opened and the machine withdrawn from its tapping position after the notch has been opened without the necessity of a workman going 75 near the machine. The control mechanism for this purpose is diagrammatically illustrated in Fig. 10. As there shown, the machine is preferably supported by a jib crane having a rotatable column 120 and an inclined boom 121 pivotally connected at its lower end to the column and tied at its upper end to the column by means of a rod 122. At the outer end of boom 120 there is attached for vertical adjustment a bar 122^a 80 provided at its lower end with a hook 123 for engaging a suspending member 124 attached to a bail 125 pivotally connected at its sides to the machine. The connection of bail 125 to the machine is through bars 126 (Fig. 2) provided with a series of holes so that the machine may be engaged at various longitudinal positions to secure desired balance. For turning the crane to remove the machine from tapping position, crane column 120 may be provided with a drum 127 engaged at one end by a cable 128 attached to a piston rod 129. This rod is attached to a piston 130 in a pressure fluid cylinder 131, to the opposite ends of which pressure fluid 90 may be admitted and exhausted through pipes 132 and 133. These pipes are connected to a compound valve 134 attached at its inlet by a pipe 135 to a motive fluid supply pipe 136.

Motive fluid, such as compressed air or steam, may be supplied to the machine from any suitable source. As shown in Fig. 10, a pump or blower 140 is provided for supplying compressed air to pipe 136, and also to a pipe 141 leading to flexible pipe 16 for supplying compressed air to engine cylinder 5, pipe 141 being provided with a valve 142 for controlling flow through it. Beyond valve 134, pipe 136 is provided with a valve 143 for controlling flow through it to pipe 83, which, as previously explained, is the source of motive fluid supply for operating the mechanism for clamping the engine cylinder to the machine frame, and also for operating the mechanism for anchoring the forward end of the machine. The valve 143 is provided with an outlet 144 for exhausting air from the anchoring mechanism cylinders at the completion of a tapping operation.

During the operation of the machine it is desirable for the operator to observe the varied lengths of stroke of the drill rod so that the reciprocating engine may be properly advanced from time to time. For this 130

purpose, the outside of the machine is provided with a stroke indicator comprising a hand 150 and a dial 151, the hand being adapted to be swung in coordination with the stroke of the engine piston to indicate the length of the stroke. The mechanism for operating this hand is indicated in the drawings as being the same as that disclosed in my prior Patent No. 1,276,252, to which reference may be made for its detailed construction and operation.

A further feature of the invention has to do with the provision of means for protecting the thread of feed screw 13 against the dust, grit and sparks which prevail in the vicinity of a metallurgical furnace particularly during a tapping operation, the means to this end varying in position as engine cylinder 5 is moved forwardly. For this purpose the portion of screw 13 to the rear of cylinder 5 is protected by a thin flexible metal curtain 160 (Figs. 2 and 3) attached at one end to a spring-actuated roller 161 mounted at the rear of the machine, and at its other end to the rear of cylinder 5. The sides of curtain 160 ride in grooves 162 at the edges of a transverse partition 163 arranged above screw 13 and provided with a central gap for the reception of cylinder arms 14. While a similar screw protector may be provided forwardly of the cylinder, it is preferred to use a rigid plate 164, the edges of which ride in grooves 162 and the end of which is attached to the cylinder. As cylinder 5 is moved forwardly and rearwardly curtain 160 unrolls and rolls so that it continuously closes the gap in partition 163 between the cylinder and the rear of the machine, and plate 164 moves forwardly and rearwardly to close such gap in front of the cylinder.

When the machine is used for tapping blast furnaces, it is preferred to provide a machine for each furnace. When this is done the machine may be so adjusted with relation to its supports that each tapping operation will be in the direct line of the iron notch 101 (Fig. 1) with the result that the body of the furnace through which the notch extends will not be weakened by perforating holes in different directions through it. For so adjusting the machine, it is placed in position in front of a furnace, and, by adjusting bar 122^a (Fig. 10) on the jib crane, the rear end of the machine is brought to proper elevation. In effecting this general adjustment, lug-engaging clamps 104 (Figs. 1 and 2) at the forward end of the machine are adjusted in slots 108 so that they will properly engage lugs 103 when the machine is at the proper inclination to bring the drill rod 25 in direct alignment with the notch. While not operating, the machine is normally supported in a horizontal position by the jib crane through the bail 125 of the machine,

the attachment of the bail to the machine being such that when the reciprocating engine is moved to its rearmost position the machine will balance backwardly. To avoid its tipping backwardly too far, the rear end 70 of the machine may be attached to the upper end of bail 125 by a flexible cable or the like 152 (Fig. 1).

When it is desired to tap a notch, the crane is turned to move the machine to tapping position, and the operator, through controller 90, runs the reciprocating engine forwardly a sufficient amount to balance the forward end of the machine downwardly so that clamps 104 engage lugs 103. The operator 80 then turns valve 143 (Fig. 10) to permit compressed air or other pressure fluid to flow through pipes 83 and 114 to cylinders 112 to cause the lower ends of lever 105 to press against lugs 103 so that such lugs become 85 firmly engaged between these levers and clamping brackets 104. The operator then sets the reciprocating engine in operation by opening valve 142 to permit the flow of pressure fluid to engine cylinder 5. By observing indicator hand 150, the operator is able to judge the length of stroke of the drill, and as such length increases he intermittently operates controller 90 to advance the engine. While motor 10 is idle, controller operating 90 lever 91 is at its central position (Fig. 11), in which a circuit is closed through electromagnet 86 to cause valve 81 to be opened so that pressure fluid is supplied through such valve and pipe 75 to the lower face of piston 47 in cylinder 46. This moves the piston to its uppermost position and causes the floating equalizing levers attached to the lower end of piston rod 48 to bring clamping blocks 52 and 55 into firm engagement 100 with the inturned flanges of frame side members 1 and 2. By so clamping the engine to the frame, the impact of drill rod 25 is directly resisted by the frame of the machine rather than by feed screw 13.

To advance the reciprocating engine, the operator turns controller handle 91 so that its indicator arm moves to the left as viewed in Fig. 10, and during such movement of the controller arm magnet 86 is first deenergized 115 to permit valve 81 to close, and magnet 87 is energized to open valve 82 so that pressure fluid is exhausted from the lower side of clamp-controlling piston 47. This permits the levers attached to piston rod 48 to release their pressure upon clamping blocks 52 and 55, which operation is always effected prior to the completion of a circuit through motor 10 for advancing the machine. Hence, when the motor is operated 120 the reciprocating engine cylinder is free to move upon the frame. As soon as the engine has been moved forwardly the required amount, the controller is again moved to neutral position, and while being so moved 125

the reverse operation of magnets 86 and 87 takes place with the result that the frame-engaging clamps are again caused to lock the cylinder upon the frame. This operation is repeated until the notch has been entirely opened.

When the notch has been opened, that is to say when iron has been reached, the operator moves controller handle 90 to the position for reversing the motor so that it will move engine cylinder 5 rearwardly of the machine to withdraw the drill rod. By causing the engine cylinder to move to its rear-most position, the machine tends to tip backwardly. Valve 143 is then turned to permit the pressure fluid in cylinders 112 to escape through exhaust outlet 144 of valve 143 (Fig. 10) and simultaneously therewith springs 113 in cylinder 112 move piston rods 20 110 inwardly to release the lower ends of levers 105 from their engagement with lugs 103. The machine then balances backwardly on its support and is removed from the front of the furnace by operating valve 134 to admit pressure fluid to the right end of cylinder 131 to cause its contained piston 130 to move to the left to revolve the jib crane on its vertical column 120. The machine then stands idle until its use is required for again tapping a notch, and while it is idle a new drill rod 2 may be attached to it if necessary.

According to the provisions of the patent statutes, I have explained the principle and operation of my invention, and have illustrated and described what I now consider to represent its best embodiment. However, I desire to have it understood that, within the scope of the appended claims, the invention may be practiced by other forms of construction and other details of mechanism than particularly shown and described herein.

I claim as my invention:

45 1. In a machine for tapping metallurgical furnaces, the combination of a frame, a reciprocating engine mounted for longitudinal movement thereon, means for moving said engine on said frame, and means coordinated with said engine moving means and effective while the engine is stationary upon the frame for clamping the engine to the frame whereby impact of the engine is resisted by the frame.

55 2. In a machine for tapping metallurgical furnaces, the combination of a frame, a reciprocating fluid pressure engine mounted for longitudinal movement thereon and comprising a cylinder and a piston rod having a tapping tool attached to it, means for moving said engine longitudinally upon said frame, and means effective when said cylinder is stationary upon said frame for clamping the cylinder to said frame to resist impact of the tapping tool.

3. In a machine for tapping metallurgical furnaces, the combination of a frame, a reciprocating fluid pressure engine mounted for longitudinal movement thereon and comprising a cylinder and a piston rod having a tapping tool attached to it, means for moving said cylinder longitudinally upon said frame, and pressure-fluid operated clamping mechanism attached to said cylinder for engaging said frame to resist impact of said tapping tool.

4. In a machine for tapping metallurgical furnaces, the combination of a frame, a reciprocating fluid pressure engine mounted for longitudinal movement thereon and comprising a cylinder and a piston rod having a tapping tool attached to it, a feed screw rotatably mounted in said frame and engaging said cylinder for moving it upon the frame, a motor having driving connections with said screw for rotating it, and means attached to said cylinder for engaging said frame to resist impact of said tapping tool, said means being rendered ineffective during the operation of said motor.

5. A machine for tapping metallurgical furnaces, the combination of a frame, a reciprocating engine mounted for longitudinal movement thereon, a tapping tool connected to said engine for reciprocation thereby, a motor for moving said engine longitudinally upon said frame, a controller for said motor, and mechanically actuated means controlled by said controller for locking said engine to said frame, said means being ineffective during the operation of said motor for moving said engine upon the frame.

6. In a machine for tapping metallurgical furnaces, the combination of a frame, a reciprocating engine mounted for longitudinal movement thereon and provided with a tapping tool adapted to be reciprocated by the engine, a motor for moving said engine upon said frame, clamps attached to said engine for engagement of said frame, a fluid pressure cylinder attached to said engine, and pressure equalizing connections extending from said fluid pressure mechanism to said clamps for binding them upon the frame.

7. In a machine for tapping metallurgical furnaces, the combination of a frame, a reciprocating fluid pressure engine mounted for longitudinal movement thereon comprising a cylinder and a piston rod, a tapping tool attached to said rod, a feed screw rotatably mounted in said frame and operatively connected to said cylinder for moving it longitudinally upon the frame, a motor for rotating said screw, clamping bars attached to said cylinder in position for engaging said frame, a fluid pressure mechanism attached to said cylinder, and pressure equalizing levers extending from fluid pres-

sure mechanism to said clamps for bringing them into engagement with said frame, said fluid pressure mechanism being rendered ineffective when said motor is operated to move 5 said cylinder upon said frame.

8. In a machine for tapping a metallurgical furnace, the combination of a frame, a reciprocatory engine mounted for longitudinal movement thereon and having a tapping 10 tool attached to it, a motor operatively connected to said engine for moving it longitudinally upon said frame, pressure fluid operated mechanism attached to said engine for clamping it to said frame, electrically 15 operated valves for controlling flow of pressure fluid to and from said mechanism, and means coordinated with the operation of said motor for controlling said valves to supply pressure fluid to said mechanism when said 20 motor is idle and from said mechanism prior to the operation of the motor.

9. In a machine for tapping metallurgical furnaces, the combination of a frame, a reciprocatory engine mounted for longitudinal 25 movement upon said frame, anchor-engaging clamps attached to said frame for holding the machine in proper tapping position, and mechanically operated mechanism for controlling said anchor-engaging means.

10. In a machine for tapping metallurgical furnaces, the combination with a frame and a reciprocatory tapping engine mounted for longitudinal movement thereon; of clamps attached to said frame for engaging 30 machine-anchoring members, and prime movers attached to said clamps for operating them, the operation of said prime movers being controllable at a distance from said machine.

11. In a machine for tapping metallurgical furnaces, the combination with a frame, and a reciprocatory tapping engine mounted for longitudinal movement thereon; of clamps including pivoted levers attached to 45 said frame for connecting said machine to anchoring members, and fluid pressure mechanism for moving said levers.

12. In a machine for tapping metallurgical furnaces, the combination with a frame 50 and a reciprocatory tapping engine mounted for longitudinal movement thereon; of clamps including pivoted levers attached to said frame for connecting the machine to anchoring members, fluid pressure cylinders 55 attached to said levers for moving them in one direction, and springs for moving said levers in the opposite direction.

13. In a machine for tapping metallurgical furnaces, the combination of a frame, 60 a reciprocatory engine mounted for longi-

tudinal movement thereon and comprising a cylinder and a piston, a cross head attached to said piston and mounted for longitudinal movement on said frame, an axially rotatable spindle attached to said cross head, 65 means for attaching a tapping tool to said spindle, a ratchet wheel rotatably mounted on said cross head and having bevel pinion connections with said spindle for rotating it, an arm mounted for oscillatory movements 70 on said cross head and provided with a pawl for engaging said ratchet, and a link extending between said arm and said cylinder whereby the reciprocation of said cross head rotates the spindle. 75

14. In a machine for tapping metallurgical furnaces, the combination of a frame, a reciprocatory engine comprising a cylinder a piston rod and a cross head attached to the rod, means for attaching a tapping tool to 80 said cross head, said cylinder and cross head being provided with rollers resting upon said frame for free longitudinal movement of the cylinder and cross head upon the frame, and a motor for moving said cylinder 85 upon said frame.

15. In a machine for tapping blast furnaces, the combination of a frame, a reciprocating engine mounted for longitudinal movements on said frame and provided with 90 a tapping tool, anchor-engaging clamps attached to the forward end of said frame for holding the machine in tapping position, mechanically operated mechanism for controlling said anchor-engaging means, and a 95 yoke pivotally attached to said frame intermediate of its ends for supporting the machine, the rearward end of the machine balancing downwardly when said engine is at 100 its rearmost position on said frame and balancing upwardly when said engine is moved forwardly whereby said clamps may be moved from and to anchor-engaging position.

16. In a machine for tapping metallurgical furnaces, the combination of a frame, a tapping engine, a cylinder mounted for longitudinal movement on the frame, a feed screw rotatably mounted in said frame below said cylinder for moving the cylinder upon 110 the frame, said cylinder being provided with a depending arm for engaging said screw, a partition extending transversely of said frame above said screw and having a gap for the reception of said cylinder arm, and 115 closures attached to the ends of said cylinder and movable therewith to close said partition gap.

In testimony whereof, I sign my name.
BENJAMIN J. MULLEN.
